ELECTRICAL CONDUCTOR

Filed March 15, 1928.

INVENTOR:
Daniel H. Murphy
BY R. H. Fair, Jr.

ATTORNEY

UNITED STATES PATENT OFFICE

DANIEL H. MURPHY, OF WEST HARTFORD, CONNECTICUT, ASSIGNOR, BY MESNE ASSIGNMENTS, TO NATIONAL ELECTRIC PRODUCTS CORPORATION, OF NEW YORK, N. Y., A CORPORATION OF DELAWARE

ELECTRICAL CONDUCTOR

Application filed March 15, 1928. Serial No. 261,944.

This invention relates to insulated electrical conductors, and more particularly to conductors having their outer jackets colored in a novel manner to give them a distinctive appearance.

It is important that wires and cables be identified or have a distinctive appearance to distinguish one type of wire or cable from another, and also for the purpose of identifying the polarity of wires in an installation. It has therefore been proposed heretofore to form the protecting covering upon different conductors of different colored strands. For example, it is customary to form the covering upon one of a pair of conductors of cotton yarn having the natural white color, and the covering upon the other conductor of black or other colored yarn so that the two conductors can be readily distinguished.

The desired color or distinctive appearance has been imparted to covered conductors heretofore by forming the covering of dyed yarn, but this increases the cost of the insulated conductors since the effect of the dye upon the yarn is to make it tender, thus necessitating the use of a higher grade of yarn at the start to make up for the reduction in tensile strength due to the dyeing process.

In many constructions it is desirable to apply to the jacket of an insulated conductor or cable a coating of a protecting compound which will completely conceal the original color that may have been given the jacket, in which case the use of dyed yarn obviously will not impart the desired distinctive appearance to the finished product.

Having in mind the foregoing, the present invention relates to a novel construction whereby any desired color is imparted to a non-metallic sheathed conductor or cable which has been treated with a protective compound.

In carrying out the present invention, a coating of coloring matter, such as any good grade of paint that will permanently adhere to the underlying surface, is applied to the conductor jacket which has been previously treated with a protecting compound. Then over this coloring matter is placed a transparent film of wax-like material which pro-

tects the coat of coloring matter without obscuring the color. The wax material protects the coloring matter from dirt, moisture and the deteriorating action of the atmosphere. It also prevents the color from rubbing off and marking adjacent objects such as the wall or ceiling to which the conductor may be secured. Furthermore, the wax film imparts a "slick finish" to the conductor which makes it clean to handle and easy to draw through conduits and openings during installation, and the distinctive color imparted to the conductor by the coloring matter is clearly observable through the transparent film of wax.

Through the use of the present invention the insulated conductors may be given any desired color at low cost, and a further saving is secured in the manufacturing cost due to the fact that uncolored yarn may be used in the construction of all conductor insulation, thus permitting standardizations in the factory.

The various features of the invention will be best understood from the following description when read in connection with the accompanying drawings, wherein:

Fig. 1 is a perspective view of an insulated conductor embodying the features of the present invention, the different coatings being shown on different portions thereof;

Fig. 2 is a perspective view of a cable provided with a pair of different colored insulated conductors; and

Fig. 3 is a longitudinal sectional view through mechanism for applying a film of wax to the colored conductor.

The present invention may be employed to impart any desired color or distinctive appearance to insulated wires, cables and protecting tubing, and may be employed upon insulating jackets that are woven, braided, wrapped or otherwise constructed.

The insulated electrical conductor illustrated in the drawing is formed of a conductor wire 10 about which is provided a jacket 11 of rubber or other suitable material, and over the jacket 11 is provided a protecting covering 12 which is shown as braided, 100

but as above pointed out may be otherwise constructed.

Upon the outer surface of the covering 12 is provided a coating 13 of an adhesive compound, which preferably, although not necessarily, is moisture-proof and flame-repellent, and this compound should possess the property of remaining elastic or flexible over a long period of time so that it will not become hard and brittle. While various sticky materials may be used to form the coating 13, stearin pitch is peculiarly well adapted for this purpose as it is fire-repellent to a high degree, and retains its plastic, rubbery character over a long period of time, while it is sufficiently adhesive to firmly adhere to the surface to which it is applied.

After the stearin pitch or other protecting compound 13 has been dried or otherwise treated to render it dry and firm upon the conductor jacket, the color coating is applied. The coloring matter used may be ordinary paint or pigment which will not become brittle when dry and crack under the flexing of the cable and it may be applied to the covered conductor by passing the conductor through a bath of the coloring matter and then wiping off the excess coloring, but care should be used in controlling the speed of the cable through the tank, and also the thickness of the coloring fluid, to secure a satisfactory coating which will not be too scant, or too thick and gobby.

After the coating 14 upon the insulated conductor has dried, there is applied thereto, in accordance with the present invention, a transparent film 15 of wax-like material. This film may be applied to the colored conductor by the mechanism shown in Fig. 3 of the drawing wherein the colored conductor 14 is shown as passing from a supply reel 16 into a tank 17 containing the melted paraffin or other wax-like material. The tank 17 may be heated by the burners 18 and as the conductor 14 leaves the tank it passes through a die or wiper 19 which removes the excess wax so that only a thin protecting film 15 will remain on the colored conductor.

The wax film 15 imparts a "slick finish" to the colored conductor which is highly desirable, since it makes the conductor easier to draw through openings during installation, prevents any tendency of the color coating 14 to rub off and mark the objects against which it is placed, and it also increases the life of the underlying coatings by protecting them from the atmosphere.

The wax coating 15 when applied in the form of a thin film will not appreciably decrease the flame retarding properties of the stearin pitch 13, for, although the wax material is combustible, the very small amount of this material required to form the desired film will not be sufficient to support combustion, and it will be understood that the dis-

tinctive color imparted to the insulated conductor by the coating 14 may be clearly observed through the thin transparent film 15.

In the cable shown in Fig. 2 each of the insulated conductors 20 and 21 is similar to the colored conductor of Fig. 1 except that the conductor 20 is colored dark while the conductor 21 is given a lighter color in order that their polarity may be readily determined. About the conductors 20 and 21 is wound the insulating material 22, and these conductors are enclosed in an outer jacket 23 which if desired may be colored in accordance with the present invention.

What is claimed is:—

1. In the art of electrical insulation, a jacket for an electrical conductor formed of interlocked strands of insulating material and having applied to the jacket three distinct layers of coating material placed one over the other in an unmixed condition comprising, a flame-retarding coating of stearin pitch applied over the interlocked strands, a coating of paint applied over the layer of stearin pitch, and a transparent film of wax applied over the paint so that the color of the paint may be seen through the protecting film of wax.

2. In the art of electrical insulation, a flexible jacket for an electrical conductor formed of insulating material and provided with three distinct layers of coating material applied thereto one over the other in an unmixed condition, and comprising a flame-retarding coating of stearin pitch, a coating of coloring matter applied over said pitch to give to the jacket a distinctive color, and a film of transparent wax-like material applied over the coloring matter in non-penetrating relation with the insulating material of the jackets and so that the color of the second coating may be distinctly seen through said film.

3. In the art of electrical insulation, a cable formed of a plurality of insulated conductors each having a flexible jacket of insulating material over which is applied three distinct layers of coating material placed one over the other in an unmixed condition, and comprising a flame-retarding coating of stearin pitch applied over each jacket, a different color coating of paint applied over each pitch covered jacket to give each jacket a different color, a film of transparent wax applied over each coating of paint in non-penetrating relation with the underlying jacket and so that the color of the second coating upon each jacket may be distinctly seen through said film, and an outer jacket enclosing the different colored conductors.

In testimony whereof, I have signed my name to this specification.

DANIEL H. MURPHY.
